[57] CLAIM

The ornamental design for an alarm unit, as shown and described.

DESCRIPTION

FIG. 1 is the perspective view of an alarm unit showing my new design;

FIG. 2 is the front elevational view thereof;

FIG. 3 is the rear elevational view thereof;

FIG. 4 is the left side elevational view thereof;

FIG. 5 is the right side elevational view thereof;

FIG. 6 is the top plan view thereof; and,

FIG. 7 is the bottom plan view thereof.

FIG. 8 is a perspective view of a second embodiment thereof, wherein the only difference exist in the addition of a mounting bracket.
